UNITED STATES PATENT OFFICE.

THOMAS D. McCORMICK, OF CANTON, OHIO.

VAPOR-BURNER.

SPECIFICATION forming part of Letters Patent No. 269,083, dated December 12, 1882.

Application filed August 14, 1882. (No model.)

To all whom it may concern:

Be it known that I, THOMAS D. McCORMICK, of Canton, in the county of Stark and State of Ohio, have invented certain new and useful Improvements in Vapor-Burners; and I do hereby declare the following to be a full, clear, and exact description of the invention, such as will enable others skilled in the art to which it pertains to make and use it, reference being had to the accompanying drawings, which form part of this specification.

My invention relates to an improvement in vapor-burners; and it consists, first, in combining in the supply-pipe through which the oil passes to the burner an automatic shut-off and a screw plug or valve for controlling the flow of oil when the burner is first lighted; second, in the supply-pipe having an automatic cut-off attached directly thereto, so that the expansion of the main supply-pipe itself shall operate the automatic cut-off; third, in the combination of the main supply-pipe with an automatic cut-off which is operated by the expansion of the supply-pipe itself, one end of the rod or wire which forms the automatic cut-off being made to extend through the end of the supply-pipe, so that it can be easily adjusted so as to cut off the flow of oil sooner or later, as may be desired.

The object of my invention is to place an automatic cut-off directly in the main supply-pipe itself, and to connect this cut-off directly to the pipe, so that the contraction of the pipe itself will operate the cut-off should the flame of the burner be accidentally extinguished, and thus prevent a continued flow of oil through the burner.

The accompanying drawing represents a burner, partly in section, to which my invention is applied.

A represents a vapor-burner of any desired shape or construction that may be preferred, and B the supply-pipe through which the oil flows to the burner. At any suitable point in this supply-pipe, beyond the reach of the vapor, is placed a plug or other suitable valve, C, which is to control the flow of oil in first starting the burner into operation. This plug, when the burner is first being lighted, will be opened just far enough to allow sufficient oil to flow past it to fill the supply-pipe B and

the drip-cup which is used in connection with all burners. When the stove has been used the supply-pipe will always be more or less filled with oil, and then it will only be necessary to let just sufficient flow past the valve to fill the drip-cup in the usual manner. This plug-valve is then closed, and is not again used until the stove has to be again lighted. This plug or valve passes through a separate and distinct casting, E, of its own, which is screwed or otherwise attached to the supply-pipe, so as to form a part thereof, and in this casting E is made a suitable partition, F, as shown. Through this partition is made a hole, G, which is to be opened and closed by the automatic cut-off H. This cut-off consists of an iron rod or wire, which is screwed into the upper end of the supply-pipe itself, and has its lower end, when the burner is not in use, to fit in the hole G sufficiently tight to shut off the flow of oil, and when the burner is in use to open the hole, so as to allow the oil to flow freely through the burner. The supply-pipe B is made of some metal which is more expandable than the cut-off H, and which will expand and contract to a greater extent than the cut-off. The upper end of this automatic cut-off will have a small slot cut in it, or it may be provided with a head or handle, or be shaped in any way that fancy may dictate, so that at any time it can be adjusted by means of its screw-thread or otherwise so as to bring its inner end nearer to or farther from the hole G. This automatic cut-off is not attached to or connected with any other device than either the end of the pipe itself or that portion of the burner or other device which is to be applied to the pipe for the purpose of forming the end of the supply-pipe, and thus the automatic cut-off is dependent wholly upon the expansion and contraction of the supply-pipe itself for its operation.

The oil which remains in the supply-pipe since the last time the burner was used, or which has flowed past the plug or valve so as to fill the supply-pipe, will be sufficient to keep up combustion after the burner is lighted until the parts have become thoroughly heated, and then when the supply-pipe has become heated sufficiently to expand lengthwise the automatic cut-off will have its end lifted up

ward away from the hole G, so as to allow the oil to flow freely into the supply-pipe and keep up combustion. Should the flames become suddenly extinguished, the pipe will contract, and thus force the end of the automatic cut-off into the hole G again, so as to stop the flow of oil. By this means all accidents arising from the overflow of the oil after the flames have been extinguished are prevented.

I am aware that a copper pipe having a rod attached to it has been placed inside of an iron supply-pipe, so that the expansion of the copper pipe would cause the rod to act as a cut-off, and this I disclaim. My invention differs from this in having the cut-off secured to and operated wholly by the supply-pipe itself without the aid of any intermediate device.

Having thus described my invention, I claim—

1. A vapor-burner, a supply-pipe leading thereto, a plug or valve, C, located in the sup-

ply-pipe, and an automatic cut-off secured to the supply-pipe itself for shutting off the flow of oil after the flames have become extinguished, all combined substantially as shown. 25

2. The combination of a vapor-burner, a supply-pipe, an automatic cut-off that is attached directly to the pipe, a by-pass valve, and a perforated diaphragm, substantially as described. 30

3. The combination of a vapor-burner, a supply-pipe, an automatic cut-off which is attached directly to the pipe, and a perforated diaphragm, the upper end of the cut-off being made to extend through the pipe so that it can be adjusted, substantially as set forth. 35

In testimony whereof I affix my signature in presence of two witnesses.

THOS. D. McCORMICK.
